US00D755481S

(12) United States Design Patent
Hodges

(10) Patent No.: US D755,481 S
(45) Date of Patent: * May 10, 2016

(54) RELIGIOUS DICKIE

(71) Applicant: Cynthia P. Hodges, Burlington, NC

(US)

(72) Inventor: Cynthia P. Hodges, Burlington, NC

(US)

() Term: 15 Years

(21) Appl. No.: 29/531,823

(22) Filed: Jun. 30, 2015

(51) LOC (10) Cl. 02-01

(52) U.S. Cl.

USPC D2/854; D2/739

(58) Field of Classification Search

USPC ..... D2/500, 501, 600, 602, 605, 609, 710, D2/715–717, 724, 725, 738, 739, 741–743, D2/749, 750, 753, 759, 760, 769, 771, 780, D2/786, 812, 828, 830, 836, 839–841, 853, D2/854, 857, 860–865, 891, 900, 901, D2/999; 2/46, 49.1–49.5, 50, 52, 69, 79, 2/84, 91, 101, 103, 127, 131, 134, 145, 2/156, 207, 227, 228, 238, 247, 463, 2/468; D5/63; D24/190–191; D29/101.2, D29/101.3, 107; 40/586; 223/68; 428/15 CPC A41D 13/00; A41D 13/04; A41D 13/10; A41D 13/043; A41D 13/046; A41D 13/0506; A41D 13/0512; A41D 13/0518; A41D 13/0525; A41D 13/0556; A41D 13/0575; A41D 13/0537; A41D 13/1209; A41D 13/1227; A41D 27/02; A41D 27/12; A41D 27/13; A41D 27/20; A41D 27/205; A41D 29/00; A41D 2400/28; A45D 200/053; A45D 44/08; D06B 11/0096; D06M 10/005

(57) CLAIM

The ornamental design for a religious dickie, as shown and described.

DESCRIPTION

FIG. 1 is a top, front, right side perspective view of a religious dickie showing my new design;

FIG. 2 is a front elevational view thereof;

FIG. 3 is a rear elevational view thereof;

FIG. 4 is a right side elevational view thereof, the left side elevational view being a mirror image thereof;

FIG. 5 is top plan view thereof; and,

FIG. 6 is a bottom plan view thereof.

The broken lines in FIGS. 1–4 illustrate environmental structure that forms no part of the claimed design.

1 Claim, 6 Drawing Sheets
